UNITED STATES PATENT OFFICE.

DEWITT C. MARKHAM, OF TOWANDA, PENNSYLVANIA, ASSIGNOR TO THE EUREKA MOWER COMPANY, OF UTICA, NEW YORK.

BELL-CRANK FOR MOWING-MACHINES.

SPECIFICATION forming part of Letters Patent No. 325,950, dated September 8, 1885.

Application filed July 15, 1884. (No model.)

To all whom it may concern:

Be it known that I, DEWITT C. MARKHAM, a citizen of the United States, residing at Towanda, in the county of Bradford and State of Pennsylvania, have invented certain new and useful Improvements in Bell-Cranks for Mowing-Machines; and I do hereby declare the following to be a full, clear, and exact description of the invention, such as will enable others skilled in the art to which it appertains to make and use the same.

In mowing-machines in which the knife is operated by an oscillating bell-crank—as, for example, in the mowing-machine described in Letters Patent No. 304,837, granted to me September 9, 1884—there is a tendency to raise the end of the knife as the bell-crank plays back and forth, and thus to get the knife out of shape and prevent its easy working. The end of the bell-crank where it is connected to the knife oscillates in the arc of a circle, and is consequently raised at the limit of its motion on each side above the plane of the knife. In order that the knife may work well, there should be little or no lost motion at the point where it is connected with the lower arm of the bell-crank. It is, therefore, necessary that the knife-head, or that portion of the knife by which it is connected with the bell-crank, should be so connected with the bell-crank as to be permitted no lateral movement; but as the lower end of the bell-crank, where it is connected with the knife, constantly varies its horizontal plane as the bell-crank oscillates upon its inclined pivot, it is necessary that the knife-head be allowed vertical play in relation to the bell-crank—that is, since the knife cannot be rigidly attached to the bell-crank, the connection must be such that the knife may remain in the same horizontal plane, while that of the bell-crank varies. Connection between the knife and bell-crank, which are designed to fulfill these requirements, fail more or less in practice, since it is impossible to make such a connection which shall always work perfectly and easily; and when the connection does not work perfectly it becomes more or less rigid, the result of which is, to a greater or less extent, to cause the end of the knife to follow the circular path of the lower end of the bell-crank.

To obviate this defect is the object of this invention, and it is accomplished by forming the lower arm of the bell-crank with projections on each side, which come in contact with the knife when the bell-crank approaches its highest points and thus prevent the knife from being raised.

In the accompanying drawings, which illustrate my invention and form part of this specification, Figure 1 is a perspective view of one end of the cutter-bar of a mowing-machine, showing the bell-crank and its relation to the cutter-bar. Fig. 2 is a direct front view of the same, showing the improved construction of the bell crank, and Fig. 3 is a view illustrating the operation of the improved bell-crank.

Like letters designate corresponding parts in all the figures.

A is the finger-bar, B the knife, C the shoe at one end of the cutter-bar, and D one of the lead-wheels of a mowing-machine; E, the bell-crank which is pivoted to the shoe at a, and F the lower end of the pitman which connects the bell-crank with the operating mechanism of the mowing-machine. The lower arm, G, of the bell-crank is made hollow and tubular, and in it is inclosed a cylinder or piston barrel, M, which receives the knife-post b and forms the only connection between the knife and the bell-crank. As will be readily understood, the knife-post enters a radial aperture in the barrel M, and is free to move up and down therein. The arm G of the bell-crank is oscillated by the pitman in the same plane with the reciprocating motion of the knife. This lower arm is provided on opposite sides with projecting heels H and I, which, when the bell-crank is in a central position, as shown in Fig. 2, are both above the plane of the knife. When, now, the arm G of the bell-crank approaches its limit of motion to the right, as indicated at the right in Fig. 3, the heel H is depressed, and, coming in contact with the knife, prevents it from being raised; and when the arm approaches its limit of motion to the left, as indicated at the left in Fig. 3, the heel I is depressed, and, coming in contact with the knife, prevents it from being raised on that side.

The heel H is made longer and of somewhat

different shape, as shown, from the heel I, since there is a greater tendency to lift the knife when it approaches its limit of motion to the right, owing to the fact that at that point the end of the knife is farthest away from the nearest knife-guard J.

I claim as my invention—
The knife of a mowing-machine, in combination with a bell-crank, which imparts reciprocating motion to said knife, said bell-crank

being provided with heels on each side of its lower arm, substantially as and for the purpose set forth.

In testimony whereof I affix my signature in presence of two witnesses.

DEWITT C. MARKHAM.
